CLAIM

I claim the ornamental design for a floor cleaner, as shown and described.

DESCRIPTION

FIG. 1 is a perspective view of a floor cleaner showing the new design.

FIG. 2 is a front side view of the floor cleaner shown in FIG. 1.

FIG. 3 is a back side view of the floor cleaner shown in FIG. 1.

FIG. 4 is a first side view of the floor cleaner shown in FIG. 1.

FIG. 5 is a second side view of the floor cleaner shown in FIG. 1.

FIG. 6 is a top view of the floor cleaner shown in FIG. 1; and,

FIG. 7 is a bottom view of the floor cleaner shown in FIG. 1.

The broken lines shown in the drawings show portions of the floor cleaner that form no part of the claimed design.

1 Claim, 6 Drawing Sheets(56)
